NECKTIE HOLDER

Olof Verner Anderson, North Kingston, R.I., assignor to
Anson, Inc., Providence, R.I., a corporation of Rhode
Island

Filed Sept. 30, 1963, Ser. No. 312,447
3 Claims. (Cl. 24—52)

This invention relates to necktie holders and more particularly to the type of necktie holders consisting of a shirt front clasping member provided with a necktie encircling loop.

An object of the present invention is to provide a necktie holder comprising a shirt engaging clasp and an adjustable loop member attached thereto in such manner as to extend over or across the front of the necktie and thus confine the necktie sufficiently to prevent the tie from flapping and from excessive sidewise movement while permitting the tie to freely move in a vertical or longitudinal direction.

In necktie holders, in garment and article holders, it is common to attach the ends of a flexible member in the form of a chain, to the opposite end portions of a clasp, but, in furtherance of certain objects important from the standpoint of practical use for necktie holding purposes, the present improvements propose an adjustable necktie loop which promotes more ready and easy association of the necktie therewith and which will drape gracefully over or across the necktie.

Another object of the present invention is to provide a necktie holder which is adjustable to accommodate different widths of neckties and which, if desired, may be provided with ornamental configurations.

Other objects of the present invention will become apparent in part and be pointed out in part in the following specification and claims.

In the accompanying drawings wherein like reference characters refer to like parts:

FIGURE 1 is a front view illustrating the practical application of the invention.

FIGURE 2 is a top plan view of the necktie holder.

FIGURE 3 is a bottom plan view of the necktie holder showing the adjustable loop member in "closed" position.

FIGURE 4 is a view, similar to FIGURE 3, showing the adjustable loop in "open" position.

FIGURE 5 is a fragmentary cross sectional view taken on line 5—5 of FIGURE 3, illustrating the adjustable structure of the loop member.

FIGURE 6 is a cross sectional view taken on line 6—6 of FIGURE 3, looking in the direction of the arrows.

Referring to the drawings, there is illustrated a shirt engaging or attaching clasp 10 including a clasping bar 11 having one reverting end 11A. A clasping lever 12 is pivotally connected to reverting end 11A by means of pintle 9. A spring 8 positioned on pintle 9 has one end engaging clasping lever 12 and the other end engaging reverting end 11A. The short end of clasping lever 12 serves as a handle while the longer end with its curved, serrated inner flanged edges 13 are yieldingly urged by spring 8 to clasp the bosom pleat of a shirt 14 between the edges 13 and the rear surface of the free end of clasping bar 11. The spring 8 may be seen in FIGURE 6. The clasp as a whole is similar to the tie clasp described and claimed in the United States patent to Edwin S. Mix, No. 1,981,740, dated November 20, 1934.

2

The bar 11 has a centrally located aperture 7 for the reception of an adjustable loop member engaging ring 15. The ring 15 is preferably of such diameter that the adjustable loop member may freely pivot when the tie ends are dropped through the loop member, as illustrated in FIGURE 1, whereby the two side portions of the adjustable loop member are free to immediately assume a proper balance and drape gracefully around and across the tie in adjusted loop position.

10 The adjustable loop member, generally indicated at 16, consists of two pieces of wire, which may be either round or rectangular (as illustrated in cross section and which are bent into arcuate or elongated semi-circular loops. First half loop 17 is provided on one end with an eye 20 and on the other end a pin 22 is fastened thereto. Second half loop 18 is provided on one end with an eye 21 and on the other end a pin 23 is fastened thereto. A hollow tubular rivet 5 pivotally connects eye 20 with eye 21.

20 A sleeve 25 arcuate in shape and axially hollow, as at 26, is provided with arcuate elongated slots 27, 28 in bottom section 29. Top surface 30 may be engraved with an ornamental design or be provided with initials or remain plain. The end of loop 17 is positioned in hollow 26 with pin 22 slidably engaging slot 27. The end of loop 18 is positioned in hollow 26 with pin 23 slidably engaging slot 28. In this manner the necktie holder illustrated in the drawings is provided with loops 17, 18 which are pivotally connected for adjustable positioning in the relation of one loop to the other loop.

25 Having shown and described preferred embodiments of the present invention, by way of example, it should be realized that structural changes could be made and other examples given without departing from either the spirit or scope of this invention.

30 What I claim is:

1. A necktie holder comprising an attaching clasp, an engaging ring connected to the attaching clasp, an adjustable loop member consisting of a semi-circular first half loop, and a semi-circular second half loop, means pivotally connecting one end of said first half loop and one end of said second half loop to said engaging ring, a hollow arcuate sleeve, a second means adjustably securing an end of said first half loop and an end of said second half loop in said hollow arcuate sleeve.

2. A necktie holder comprising an attaching clasp, an engaging ring connected to the attaching clasp, an adjustable loop member consisting of a semi-circular loop provided with an eye in one end, and a second semi-circular loop provided with an eye in one end, a hollow tubular rivet pivotally connecting said first mentioned eye with said second mentioned eye said hollow tubular rivet pivotally connected to said engaging ring, a hollow arcuate sleeve having a first arcuate elongated slot and a second arcuate elongated slot, one end of said first mentioned semi-circular loop slidably engaging said hollow arcuate sleeve, a pin located in said first arcuate slot and fastened in said first mentioned semi-circular loop, one end of said second semi-circular loop slidably engaging said hollow arcuate sleeve, a second pin located in said second arcuate elongated slot and fastened in said second semi-circular loop.

3. A necktie holder comprising an attaching clasp consisting of a clasping bar having one reverting end, a clasping lever, means pivotally connecting said clasping

lever to said reverting end, a spring means resiliently urging said clasping lever into engagement with said clasping bar, an aperture centrally located in said clasping bar, a ring, means pivotally connecting said ring to said clasping bar through said aperture, an adjustable loop member consisting of a semi-circular first half loop provided with an eye on one end and a pin fastened in the other end, a semi-circular second half loop provided with an eye on one end and a pin fastened in the other end, a hollow tubular rivet connecting said first mentioned eye with said second mentioned eye, said hollow tubular rivet pivotally connected to said engaging ring, a hollow arcuate sleeve having a first arcuate elongated slot and a second arcuate elongated slot, said semi-circular first half loop slidably connected to said hollow arcuate sleeve with said first mentioned pin slidably engaging

said first arcuate elongated slot and said semi-circular second half loop slidably connected to said hollow arcuate sleeve with said second mentioned pin slidably engaging said second arcuate elongated slot.
